(57) **CLAIM**

The ornamental design of a surgical handpiece, as shown and described.

DESCRIPTION

FIG. 1 is a front elevational view of the surgical handpiece; FIG. 2 is a left-side elevational view thereof; FIG. 3 is a right-side elevational view thereof; FIG. 4 is a rear elevational view thereof; FIG. 5 is a bottom plan view thereof; FIG. 6 is a top plan view thereof; FIG. 7 is a bottom perspective view thereof; and, FIG. 8 is a top perspective view thereof. Phantom lining, where utilized, is for illustrative purposes and is not intended to limit the claimed design to the features shown in phantom.
